UNITED STATES PATENT OFFICE.

WILLIAM M. SCHOLL, OF CHICAGO, ILLINOIS.

ARCH SUPPORT AND ANKLE-TIPPING CORRECTOR.

Application filed August 29, 1927. Serial No. 216,015.

My invention relates to devices for relieving foot pains due to ankle tipping which is induced by weak feet, usually evidenced by a weak or partially depressed arch of the 5 metatarsus. Persons suffering with outwardly tipped ankles usually walk on the outer longitudinal edge of the foot which results in undue wear upon this part of the shoe and this aggravates the trouble and 10 enhances the deformity.

The cause of this unnatural manner of walking is usually due to weak sore feet and especially to weak and depressed arches of the metatarsus and the tender parts thereof 15 and an effort to relieve the affected parts by imposing the weight of the body, which they should naturally bear, upon other parts of the foot.

The device disclosed herein is so formed 20 that it constantly tends to replace the displaced parts into their natural positions. The arch supporting parts, support and replace the metatarsal members of the metatarsus, and the outer thickened edge of the 25 cover plate lifts the outer edge of the foot above its normal altitude thus constantly tending to rock or replace the ankle and to produce correctly balanced feet.

I have found it to be expedient and ad- 30 visable to apply a remedy in the application of proper supports to correct the troubles with the arch and with the ankle at one and the same time. If the metatarsals can be restored and strengthened so that 35 there is no pain when weight is imposed thereon the confidence of the patient will operate to a great degree to straighten the ankle and if at the same time the outer edge of the foot is raised and supported the ankle 40 will soon return to its balanced position.

One of the objects of my invention is to provide an arch support and an ankle correcting means in one and the same structure.

Another object is to provide a new sup- 45 porting device of the character to be hereinafter described.

Other objects, advantages and benefits will hereinafter appear from a consideration of the following description and the accom- 50 panying drawings, wherein:

Figure 1 is a top plan view of the device.

Figure 2 is a central longitudinal section taken on line II—II of Figure 1.

Figure 3 is a transverse section taken on 55 line III—III of Figure 1.

Figure 4 is a section taken on line IV—IV

of Figure 1, showing a part of a shoe within which the device is to be placed.

In all the views the same reference characters indicate similar parts.

The foot curative device herein disclosed is designed to lay flat on the inner sole of a shoe, substantially as shown in Figure 2.

The upper plate 5 is relatively flexible and may well be of leather.

The main body part 6 of the leather plate is of substantially uniform thickness. The margin outside of the dotted line 7 is substantially twice as thick as the main body part 6. The transverse section of the strip 8 is wedge-shaped with its thicker edge lying parallel with the outer margin 9 of the plate 5. The part 8 is firmly attached to the body 6 by glue, other adhesive, or in any other satisfactory manner. A relatively rigid metal plate 10 is attached to the plate 5 near and below its front end. The plate 10 is triangular in plan and it is arched by being upwardly curved longitudinally and transversely. Only the front end 70 of plate 10 is arched or longitudinally curved as shown in Figure 2. The front end of plate 10 is also transversely curved. The longitudinal curve of the front end is made on a longer radius than is the trans- 75 verse curve. The transverse curve is shown in Figure 3. The narrow rear end is substantially flat. The width of the front end of plate 10 is just sufficient to lie under the heads of the second and third metatarsals. 80

Plates 5 and 10 are attached by rivets 11.

The front curved end of plate 5 is skived to a thin edge, as at 12. This end curve corresponds substantially with the curve of the area occupied by the heads of the meta- 95 tarsals of the foot.

Figure 4 is a section of a shoe in which the device is to be worn, the section being taken on line IV—IV of Figure 1, just behind the rear end of plate 10.

In the shoe 13 is the heel, 14 the upper and 15 the inner sole. 16 is the sole.

The device shown in Figure 1 is intended for the right foot and the shoe of Figure 4 is also for the right foot.

It will be observed that the thickening strip 8 tends to raise the outside edge of the foot and to cause the ankle to assume its normal natural position and plate 10 tends to and does raise the second and third 110 metatarsals and permits the first metatarsal to be depressed to some extent ultimate-

ly restoring the parts to their natural positions.

I am aware that many changes may be made, and numerous details of construction may be varied through a wide range without departing from the principles of this invention and I therefore do not purpose limiting the patent granted hereon, otherwise than necessitated by the claims.

10 Having described my invention what I claim is:

1. An arch support comprising an upwardly curved metal plate for underlying the second and third metatarsals only of the 15 metatarsus; an overlying flexible plate for extending from the rear of the heel to the phalanges, and a portion extending from the fifth metatarsal rearwardly along the outer edge of the plate to a point near the

front of the heel which is of greater thickness than the remainder of said plate. 20

2. In an arch support, a transversely and longitudinally arched metal plate for supporting certain of the intermediate metatarsal joints, a flexible member overlying said plate and adapted to underlie the plantar surface of a foot, and a transversely wedge-shaped strip underlying the outer margin of said flexible member for a portion of the length of said member, so that when a foot is imposed on said arch support, the three bearing points of the foot are unsupported and the foot is urged into proper position on said bearing points. 25

30 In testimony whereof I have hereunto subscribed my name at Chicago, Cook County, Illinois.

35 WILLIAM M. SCHOLL.
